US00D722630S

(12) **United States Design Patent**
Hatano

(10) **Patent No.:** **US D722,630 S**
(45) **Date of Patent:** **** Feb. 17, 2015**

(54) **TRANSMISSION CASE FOR AUTOMOBILES**

(71) Applicant: **Honda Motor Co., Ltd.**, Tokyo (JP)

(72) Inventor: **Takahiro Hatano**, Wako (JP)

(73) Assignee: **Honda Motor Co., Ltd.**, Tokyo (JP)

(**) Term: **14 Years**

(21) Appl. No.: **29/483,923**

(22) Filed: **Mar. 4, 2014**

(30) **Foreign Application Priority Data**

Sep. 4, 2013 (JP) 2013-020457

(51) **LOC (10) Cl.** **15-99**

(52) **U.S. Cl.**

USPC **D15/149**

(58) **Field of Classification Search**

USPC D12/126; D15/5, 148, 149; 123/41.86,
123/432
